FIREMAN'S TOOL

Theodore Ziaylek, Jr., P.O. Box 292,
Yardley, Pa. 19068

Filed Mar. 9, 1970, Ser. No. 21,828

Term of patent 14 years

Int. Cl. D8—02

U.S. Cl. D8—89

FIG. 1 is a perspective view of a fireman's tool embodying the ornamental design of the present invention;

FIG. 2 is an elevation of the fireman's tool of the present invention as seen from the left hand end of FIG. 1, broken away for convenience of illustration;

FIG. 3 is a plan view of the fireman's tool of the present invention as seen from the top of FIG. 1, and

FIG. 4 is a vertical sectional view of the tool illustrated in FIG. 1 taken on the line 4—4 thereof.

I claim:

The ornamental design for a fireman's tool, as shown and described.
